Isaac Heller, 2080 Arrowwood Drive, Scotch Plains,
N.J.

Filed Oct. 18, 1962, Ser. No. 72,183

Term of patent 14 years

(Cl. D34—5)

FIGURE 1 is a top plan view of a game board showing our new design;

FIGURE 2 is a front elevation thereof taken from the plane of the line 2—2 of FIGURE 1, the rear elevation being the same;

FIGURE 3 is a side elevation thereof taken from the plane of the line 3—3 of FIGURE 2, the other side elevation being the same; and

FIGURE 4 is a transverse vertical sectional view on the plane of the line 4—4 of FIGURE 1.

The essential features of our design reside in the combination of a labyrinth playing area having a pyramidal projection in the center thereof on a game board having six horseshoe-like pockets about the periphery that com-

prise sloping walls which form feet at the base of each pocket, all as shown.

We claim:

The ornamental design for a game board, as shown and described.
